ELECTRIC RESISTANCE HEATER FOR HIGH TEMPERATURES.

1,426,245.

Specification of Letters Patent. Patented Aug. 15, 1922.

Application filed December 10, 1919. Serial No. 343,619.

To all whom it may concern:

Be it known that we, Dr. BRUNO BAUER and Dr. ALFRED VON ZEERLEDER, both citizens of the Swiss Republic, the former residing in Zurich, the latter in Geneva, Switzerland, have invented new and useful Improvements in Electric Resistance Heaters for High Temperatures, of which the following is a full, clear, and exact specification.

10 The employment of resistance masses, which are stable at high temperatures is known for electric laboratory furnaces, in using these masses for making electric heaters for industrial purposes the supply of current is beset with difficulties, which render their use difficult in practice. Then, too, the use of resistance rods of materials stable at high temperatures is also known. Such rods however have not been found satisfactory, 15 since they are extremely fragile and, in contact with foreign bodies, are subjected to decomposition, to say nothing of the fact that the supply of the current is technically unreliable. For these reasons, none of the 20 forms hitherto known has stood the test of practice.

The present invention relates to an electrical resistance heater for high temperatures, which is extremely suitable for technical employment.

This resistance heater combines with a jacket like heating body of mouldable stable resistance material, i. e. of such resistance material that is not affected at high temperatures, current supplying rod-like electrodes of a similar or analogous material i. e., not fusing at the temperatures under notice, up to about 2,000° C., these electrodes being arranged at both ends of said resistance heating body and extending far enough into the body of the heater to permanently secure a reliable supply of current to the same. These electrodes may be made of silundum, carborundum, kryptol (that is a mixture of graphite, carborundum and clay) etc., or of carbon or graphite rods, which at the highly heated points assume a protective layer at the expense of the resistance mass. Preferably they project from above and below into the heating mass to convey the current along the wall of the crucible.

In such an electric resistance heater applied to furnaces, the masonry or refractory material surrounding the resistance heating mass

becomes electrically conductive at high temperatures, so that a shunt can be formed through the masonry between the current supplying poles. To obviate this, the envelope of masonry or refractory material is advantageously provided with one or more transverse insulating partitions or screens preventing any electric shunt through the heated masonry.

To protect the current supply poles against the high temperatures existing within the furnace and to thus efficiently save the same, the current supply poles can be arranged near to the outer wall of the masonry of the furnace and, if desired, a layer of heat insulating material, such as burnt clay powder, quartz-sand, asbestos etc., may be inserted between them and the resistance heating body.

When using a mouldable resistance heating mass of the kind described, it has been found, that its resistance is greater in cold state than after its heating. It results therefrom that for the starting of the heating body, higher tensions are required than afterwards, if the full charge shall immediately be obtained. To lessen this drawback, there can additionally be inserted into the resistance mass a certain number of thin rods of similar or analogous material to that of the current supply electrodes. These additional rods conveying the current when being in the cold state, become rapidly heated and then transfer their heat to the surrounding heating mass, so that the specific resistance therof is diminished and the current can be turned over to the heating mass. The current received by said additional rods is only small as compared with that which is received by the heating body in the hot state.

Figures 1 and 2 of the accompanying drawing show, by vertical section, two forms of the improved resistance heater as being applied to a crucible furnace.

In the first form represented by Figure 1, the entry and exit of the current take place at the poles 2, of metal, carbon, or graphite, which may be provided with water cooling means at 3, and carry the current supplying electrodes 1, in the form of rods, arranged in the upper and lower part of the resistance heating body 4 of the heater. The electrodes 1 consist of a similar or analogous resistance material stable at high tempera-

tures, or infusible, to that which constitutes the mouldable resistance body 4 that serves for the actual heating, and they extend sufficiently far into the interior of the heating body 4 to furnish a steady passage for current under all circumstances, even if the heating mass should sinter. By the use of similar materials or of materials of the same nature for the electrodes and the heating body, a chemical action between the two, which might result in their decomposition, is avoided. Then too, the electrodes and the heating body have the same co-efficient of expansion during heating. By using electrodes which are stable at high temperatures we obtain a great security in working as compared with metallic ones.

The heating mass is so formed in the example shown in the drawing as to form a closely fitting heating jacket for a crucible. The resistance heating body can very extensively be adapted to the needs of industry. It may be used in the form of a jacket for rotary or muffle furnaces, or as plates or rods for reheating, hardening, or hearth furnaces, or other heating apparatus. The heater may be constructed for continuous or single-phase or polyphase current. By suitably modifying the cross section of the heater, the lowest or highest heat may be applied at fixed zones of the heater. For instance, by enlarging the cross section of the heater at the current supplying poles injurious heating of the latter may be avoided, and, similarly, by diminishing the cross section of the heater at the lower part of the crucible higher heating may be effected.

In order to avoid any current losses through the masonry 5 surrounding the heating body 4, at the existing high temperatures, the masonry 5 is provided with electrically insulating transverse partitions or screens 6, for example of mica or asbestos, arranged to prevent any electric shunt through the heated masonry. The number of such protective screens may vary. A single one may suffice under certain circumstances.

Fig. 2 shows a second form quite similar to the first one with regard to the arrangement of the resistance heating body 4 and of the current supplying electrodes 1. To diminish heating of the current supply poles 2, the latter are located near to the outer wall of the masonry 5 constituting the envelope of the furnace. Whilst the lower electrodes 1 are arranged vertically, that is parallel to each other, the upper electrodes 1 lie in a horizontal plane and are radially directed to allow the mounting of the upper current supply poles 2 closely to the lateral outer walls of the masonry. Furthermore, a refractory and insulating layer 9, for example of burnt clay powder, quartz-sand, asbestos and the like, is inserted be-

tween the current supply poles 2 and the resistance heating body 4.

In this construction, besides the current supplying electrodes 1, for the purpose given above, there are still inserted into the resistance heating body 4 a certain number of thin additional rods 10 of similar material to that constituting the electrodes 1. The number of such additional resistance rods 10 depends on the size of the heating body. They are designed on the starting of the cold furnace, to rapidly heat the resistance body 4 and to thus render it better electrically conductive.

What we claim is:

1. In an electric resistance heater for high temperatures, for electric furnaces, the combination of a mouldable heating body of any resistance material stable at high temperatures, current supply poles arranged in front of the upper and lower ends of the resistance heating body, rod-like electrodes of similar resistance material to that of the resistance heating body, carried by said current supply poles and arranged so as to deeply extend from above and below into the resistance heating body, an envelope of refractory material surrounding the latter, substantially as described.

2. In an electric resistance heater for high temperatures, for electric furnaces, the combination of a mouldable heating body of any resistance material stable at high temperatures, current supplying poles arranged at the upper and lower ends of the resistance heating body, rod-like electrodes of similar resistance material, to that of the heating body, carried by said current supply poles and arranged so as to extend deeply into the resistance heating body, an envelope of refractory material surrounding said resistance heating body and a protective insulating partition or screen extending transversely through said envelope between the upper and lower current supplying poles to avoid electric shunt through the envelope when being heated, substantially as described.

3. In an electric resistance heater for high temperatures, for electric furnaces, the combination of a mouldable heating body of any resistance material stable at high temperatures, current supply poles arranged at the upper and lower ends of the resistance heating body, rod-like electrodes of similar resistance material to that of the resistance heating body, carried by said current supply poles and arranged so as to deeply extend into the resistance heating body, an envelope of refractory material surrounding the latter, said current supply poles being located near to the outer wall of the envelope and an intermediate heat insulating layer being inserted between the current supply poles and the resistance heat-

ing body, for the purpose of reducing heating of the current supply poles, substantially as described.

4. In an electric resistance heater for high temperatures, for electric furnaces, the combination of a mouldable heating body of any resistance material stable at high temperatures, current supplying rod-like electrodes of similar resistance material, arranged at the upper and lower ends of the resistance heating body so as to deeply extend thereinto and thin additional rods of similar material to that of the electrodes, inserted into the resistance heating body and

arranged for starting purposes to rapidly 15 heat the cold resistance mass and to thus increase its conductivity, substantially as described.

In witness whereof we have hereunto singed our names this 12th day of November 20 1919, in the presence of two subscribing witnesses.
